SYSTEMS OF EXPANSIBLE WELL TOOLS
Henry U. Garrett, Longview, Tex., assignor to Udell,
Inc., Longview, Tex., a corporation of Texas
Filed April 11, 1960, Ser. No. 21,333
14 Claims. (Cl. 166—196)

This invention relates to improvements in well tools, and refers more particularly to tools made up in the tubing string of a well that are expanded to engage the well casing, systems including such tools and the method of making such installations.

It is frequently desirable in present day equipment of wells for the production of oil and gas to utilize several packers in a single well to seal between the usual oil string of casing and the well tubing. For example, it is sometimes desirable to seal both above and below a producing formation in a well that is producing only from a single formation and in other wells producing from several formations it is usually necessary to provide a seal between a tubing and casing between the various producing formations.

With equipment that has been available for this purpose, trouble has been experienced in setting the packers, when a series of them are employed, with being certain that the right portion of the weight of the tubing is supported by each packer. This trouble is experienced because of the manipulation of the tubing that is required in setting the packers and any tubing hold-down devices that are employed. For example, let us consider a well having three packers where the operator desires to have 10,000 pounds of the tubing weight carried by each packer. The mere fact that the weight indicator at the surface indicates that on completion of the setting of the packers that 30,000 pounds of the weight of the tubing string had been released (over and above the weight of the tubing string beneath the lowermost packer) does not mean that this weight has been evenly distributed between the three packers. While it is not critical that each packer have a load imposed on it that is known to within a few pounds, nevertheless the load supported by each packer must be sufficient to provide the seal between the tubing and casing and should be predetermined within practical oil field tolerances. Heretofore, the division of the weight of the tubing string between the packers has frequently been such that one or more of the packers has not had sufficient load on it to provide the seal. Even if the packers are properly loaded when set, the setting of the hold-down, where one is used, may disturb the distribution of the load to the extent that a failure occurs. In any event, the operator has no way to determine just what load is supported by the various components of the installation.

It is an object of this invention to provide a well tool adapted for inclusion in a tubing string with an expandable means, for example a packer or a hold-down, which can be controlled from the surface in its setting, without requiring any manipulations of the tubing string that can affect the weight of the tubing string that has previously been imposed on a previously set packer.

Another object is to provide a well tool having relatively telescoping parts for actuating an expandable means, for example a packer or a hold-down with a means for holding the parts in a relative position with the packing means contracted, and a means for releasing the holding means by an operation controllable from the surface which is independent of any manipulation of the tubing string.

Another object is to provide a well tool, for example

2

a packer or hold-down, with a pressure operated means to prevent premature setting of the well tool which may be released by an operation controllable from the ground surface without affecting the amount of the weight of the tubing string that is borne by the well tool or any previously set device.

Another object is to provide a well tool, as a packer or a hold-down, with a lock means to prevent its premature setting in which a wire line operation is used to release the lock whereby the packer may be set with a predetermined load by releasing a predetermined portion of the tubing weight to set the packer.

Another object is to provide a well tool, as a packer or a hold-down, with a lock means having a fluid filled chamber which holds the tool contracted, with means to vent the chamber to release the lock without a manipulation of the tubing string that can affect the load on any component in the tubing string due to any portion of its weight.

Another object is to provide a tubing system with a series of well packers therein in which each of the packers may have a selected portion of the weight of the tubing string supported thereon.

Another object is to provide a tubing system with a series of well packers therein in which a selected load may be placed on each of the packers and a hold-down is provided on the tubing string above the packers so that the loading on the packers will not be disturbed.

Another object is to provide a tubing system with a series of well packers therein in which a selected load may be placed on each of the packers and a hold-down is provided on the tubing string above the packers so that the loading on the packers will not be disturbed, and in which the portion of the tubing above the hold-down may be released for performing various well operations.

Another object is to provide a method for setting a tubing string with a plurality of packers therein so that each of the packers will support a selected portion of the weight of the tubing string.

Another object is to provide a method of installing a tubing string with a plurality of packers therein with a selected portion of the tubing weight carried by each of the packers in which a substantial portion of the tubing above the packers may be removed without disturbing the loading on the packers.

Other and further objects of the invention will appear from the description of a preferred embodiment of the invention and from the claims.

In the accompanying drawings which form a part of the instant specification and wherein like reference numerals are used to indicate like parts:

FIGS. 1A and 1B illustrate in section a cased well bore equipped with a tubing system, including packers and a hold-down embodying a preferred mode of practicing this invention;

FIG. 2 is a view upon an enlarged scale and shown partially in section, illustrating a sleeve valve illustrated opposite two of the upper producing formations in the illustrations of FIGS. 1A and 1B for the purpose of selectively establishing communication between the tubing and the producing formation;

FIGS. 3A and 3B are a view on an enlarged scale, in vertical section, of the preferred embodiment of the packer illustrated in FIGS. 1A and 1B;

FIGS. 4A and 4B are views on an enlarged scale showing the preferred hold-down tool illustrated in FIGS. 1A and 1B.

Referring to the drawings, and more particularly to FIGS. 1A and 1B the numeral 5 designates a bore hole of an oil well with a string of casing 6 and a string of well tubing 7 therein. The bore hole passes through the upper and lower producing formations 8 and 9, the casing being perforated adjacent these formations as shown at 6a and 6b.

These producing formations are isolated from each other as well as from the bottom of the well and the ground surface by a series of packers 10, the details of which are shown in FIGS. 3A and 3B. Of course, it will be understood that more than two producing formations might be involved in a single well in which case the additional formations would be isolated similarly by additional packers.

In the particular well illustrated, the bottom of the tubing is blanked off with a bull plug 11 and formation 9 is the lowermost producing formation. Of course, the invention is equally applicable to wells in which the bottom of the tubing may communicate with the producing formation through a well screen or other suitable device. The tubing string, above the uppermost packer 10 is equipped with a hold-down indicated generally at 12.

Referring to the preferred embodiment of the packers, as shown at 10, they are of the type that require a support for the tubing below the packer to hold it against downward movement. In the illustration shown the bull plug at the lower end of the tubing bears directly against the bottom of the bore hole. However, it is contemplated that any other suitable means for supporting the tubing beneath the packers can be employed, and in fact, the lowermost packer of a series may be a hook wall packer, which is conventional in the art. The hook wall packer can serve this purpose as well as to provide one of the series of packers.

The bull plug 11, or a conventional hook wall packer engaging the casing wall, if that alternative is used as lowest support for the tubing, bears all weight of the tubing string not supported at the well head or supported by frictional resistance of packers engaging the casing wall at higher locations.

The details of the construction of the packer 10 are shown on an enlarged scale in FIGS. 3A and 3B. The tool may be considered as made up of inner and outer coaxially aligned telescoping parts. The outer telescoping part includes a number of components, as does the inner part. The outer part has, at its upper end, a coupling nipple 13 adapted to be secured to the lower end of a joint of tubing of a tubing string. This nipple is connected to a detent housing 14 provided at its lower end with an elongate wash pipe 14a. A sleeve 15 is connected between the detent housing and a shoe 16 which makes up the lower end of the outer part. The shoe 16 abuts the upper retainer 17 of the expandable packing assembly.

The inner part of the packer includes the lower coupling nipple 18 which secures the packer to a collar 19 of the tubing string immediately below the packer. The lower retainer ring 20 of the packing assembly abuts nipple 18 and surrounds the inner mandrel 21 about which the distortable packing material 22 is lodged. The packing material may be any of the materials presently used for this purpose. Several retainer ring packing assemblies may be mounted about mandrel 21.

Sleeve 23, with a piston-like head 23a at its upper end, completes the inner part. This piston-like head fits between the wash pipe 14a and sleeve 15 and is adapted to slide therein upon relative telescoping movement of the inner and outer parts.

A number of annular seals, shown in the drawing, sealing between components that make up the inner and outer parts have not been described because it is believed that their structure and function is obvious from the drawing.

It will be noted that the inner and outer telescoping parts, when in the position shown, with the packing means 22 contracted are adapted to be moved in telescoping

relationship in a direction to radially expand the packing means by forcing the upper and lower retainer rings 17 and 20, closer together. Telescoping parts to accomplish this function and result are known to the art, but some of the novelty here consists in providing a means to prevent premature expansion of the packer, which is releasable, without altering the load on the packer or lower devices in the tubing. This means must, of course, be releasable by remote control from the surface, and in its preferred form is adapted to be released by a wire line operation which is wholly independent of any manipulation of the tubing string.

In the form illustrated, this releasable means includes a fluid filled detent mechanism which may be released by manipulation of a wire line operated tool. The detent includes the sealed chamber 24 between the wash pipe 14a and sleeve 15, the lower end of which is sealed against the escape of fluid by chevron packing rings 25. The O-ring packing 26a seals between the piston-like head 23a and the wash pipe 14a. It is seen that the face end of head 23a confronts the downwardly facing shoulder 14b so that fluid trapped in chamber 24 resists movement of the piston-like head 23a within the chamber. A hydraulic fluid is preferred for chamber 24.

Means are provided to release the detent by venting the fluid from chamber 24. These include the spring pressed valve 26 and its registering seat 27. Of course, the spring and the pressure in chamber 24 will urge the valve member against the seat but this may be overcome by the pin 28 which presses against the tail piece on valve 26. The pin 28 is adapted to be lowered to open the valve when the sleeve 29 is lowered, due to a cam and follower connection between the sleeve and the pin 28. This connection includes the cam part 30 urged by the leaf spring 31 against the cam notch 29a formed in the periphery of sleeve 29. Cam part 30 has a cam notch 30a engaging the follower end of pin 28 and it is obvious that when sleeve 29 is moved downwardly part 30 is moved radially to depress the pin 28 and open valve 26. Set screw 36 engages a vertical slot 29b in sleeve 29 to keep the sleeve properly aligned relative to the cam part 30. Chamber 24 is thus vented to the exterior of the packer through vent 28a.

To seal the opening, in which cam part 30 resides, from the interior passageway through the packer, is the function of seals 32 and 33. These can be dispensed with if the opening in which cam part 30 resides is closed to the exterior of the tool and chamber 24 is vented into the interior of the packer. The detent housing contains notches 14d and 14e in which the snap ring 34 resides to hold the sleeve in a given position until sufficient force or impact is applied to it to move it either to raised or lowered position. Upward movement of the sleeve is limited by the lower end of nipple 13 and downward movement is limited by the inner taper 14c of the detent housing. The means for delivering the impact or moving force to the sleeve for shifting it is illustrated diagrammatically at 35. This shifting tool may be of the type illustrated and described at page 1976 of the "Composite Catalog of Oil Field Equipment and Services," 1957, 22nd edition, in Figs. 2 and 3, identified as the type "B-3" shifting tool. Inasmuch as these shifting tools are well known commercially available devices, a detailed discussion of the tool will be dispensed with.

It is believed that the operation of the packer is apparent from the foregoing description. Upon telescoping movement of the inner and outer parts from the position shown in FIGS. 3A and 3B, in a direction to bring the upper and lower retainer rings of the packing assembly together, the packing means 22 is expanded radially to contact the well casing 6. However, this telescoping movement is resisted by the fluid within chamber 24, preferably the chamber is nearly substantially filled with hydraulic fluid with only a relatively minor air space being left. In fact, in low temperature installations the chamber 24 may be filled as nearly completely with hydraulic fluid

as is practically possible so that substantially no relative movement of the inner and outer parts is permitted until the fluid has been released. However, due to the expansion of the liquid upon an increase in temperature and the high temperatures now prevalent in some localities in which such packers may be used, it is desirable to provide at least a small gas-filled space within the chamber to accommodate the expansion of the liquid without building up undue pressure within the chamber. Also, it is contemplated that chamber 24 may be filled with gas under pressure of a sufficient magnitude to prevent premature setting of the tool while the tubing string with the packers is being run into the well. Also, it is contemplated that a mechanical detent may be substituted for the fluid filled detent. The hydraulic detent is preferred because it does not require a high initial pressure and is very simple, yet is extremely rugged and is capable of transmitting very large loads between the inner and outer parts while preventing relative movement therebetween.

In making an installation where several packers are to be set, the packers are made up as a part of the tubing string as the tubing string is lowered into the well. They are, of course, properly spaced in accordance with the usual practice to locate the packers in the desired position within the well. To set the packers the wire line sleeve shifting tool 35 is lowered within the tubing string to a position suitable for first releasing the detent mechanism of the lowermost packer. With the particular tool referred to and illustrated in the Composite Catalog, the shifting tool is lowered beneath the lowermost packer and then raised until the upwardly facing dogs engage the lower shoulder of the sleeve. Sufficient force is exerted either through a pull or through impact to shear the pin which is effective to hold the upwardly facing dogs expanded. This permits the upwardly facing dogs to be retracted by internal springs but simultaneously releases downwardly facing dogs so that they can be utilized. The tool is then pulled upwardly through the sleeve of the lowermost packer, which is permitted by the yielding action with which these dogs are mounted on the tool. The tool may then be operated to shift the sleeve 29 downwardly.

The lower end of the tubing string is resting against the bottom of the hole but at this time the majority of the weight of the tubing string is held by the elevators at the top of the well. The weight of the tubing string is known and the weight held by the elevators is indicated by a weight indicator at the ground surface. Sufficient amount of the weight is then allowed to be released to account for the weight of the tubing beneath the lowermost packer and an additional amount which is predetermined or selected to be the amount desired to be applied to the packer and effective to expand the packing means 22 to provide a seal. Inasmuch as the detent has been released, this slack-off of weight results in telescoping movement of the inner and outer parts of the packer to expand the packing material into engagement with the wall of the well casing. This expansion of the packing material takes place immediately upon application of the weight to the outer part. After application of only a relatively small amount of the weight of the tubing to the tool the packing material is expanded into contact with the wall of the casing. The friction engagement of the packing material with the well casing provides an anchor at this point for supporting additional load applied to the device as additional weight is relieved at the elevators. The amount of load required to expand the packing until the friction between the packing and the casing is sufficient to support the load will depend upon the characteristics of the packing material, such as hardness, but with any given packer will be known within practical limits. This makes it possible to support on each packer a known weight of tubing or load within practical oil field tolerances or limits.

For example, if it is calculated that the weight of the tubing beneath the lowermost packer is 1,000 pounds

and the weight of tubing in addition to this that is required to collapse the packing material until it frictionally engages the well casing is 200 pounds, and it is desired to have approximately 10,000 pounds supported by the lower packer to maintain the sealing engagement between the packing material and the well casing, as well as with the mandrel 21, then approximately 11,200 pounds of the total load of the tubing string will be relieved at the ground surface. It is, of course, to be understood that practical oil field tolerances permit a substantial tolerance or range of operation, and though in the specification and claims it is indicated that the selected or predetermined load is imposed on the packer, it means within this wide tolerance. Usually a variation in the order of ten percent or even somewhat higher is permissible.

After setting the first or lowermost packer, the sleeve shifting tool is then raised to the next higher packer and is operated to release the detent mechanism of this packer. At this point the elevators are operated to release an additional preselected amount of the weight of the tubing string. The release of the weight may be either before or after the release of the detent.

In selecting the load to be imposed on the lower of two packers it must be borne in mind that the load cannot be less than the weight of the string of tubing between the two packers unless a suitable anchor is placed in the string to engage the casing and thereby support the excess of the weight of the tubing string between the two packers. It is seldom that this consideration is material, because the selected load on any packer usually, but not necessarily, ranges from 7,000 to 10,000 pounds. 1,000 feet of two and one-half inch API tubing weighs a little over 6,000 pounds, the exact weight depending upon the particular tubing employed. 2,000 feet of two inch API tubing weighs in the neighborhood of 9,000 pounds. Packers are seldom spaced far enough apart that the weight of intervening tubing will exceed 10,000 pounds.

The successively higher packers may be consecutively set in the manner described for setting the lowermost packer. If desired, a hold-down may be placed in the tubing string above the uppermost packer or at any other place that it may be desired, which will be useful for holding the load on the packers beneath it while permitting the tubing string thereabove to be parted for the purpose of carrying out any desired oil well operation, or even production of oil or gas through the casing from a point in the well above the hold-down.

A preferred hold-down is shown in FIGS. 4A and 4B, which may also be set without manipulation of the tubing other than to place the desired load on the device. In principle it is much the same as the packer previously described, except that the expandable means are locking dogs in place of the expandable packing means. The locking dogs are expanded to engage the casing upon telescoping movement of the parts in one direction. A releasable means is utilized to hold the telescoping parts in position to maintain the locking dogs retracted, which is released by remote control without manipulation of the tubing in any manner that would affect the load placed either on the hold-down or the packer therebelow.

The tool comprises inner and outer parts which are mounted for telescoping movement. The outer part consists of a detention housing 40 which may be connected at its upper end to the lower end of the adjacent tubing string through the coupling 41. Preferably the coupling 41 has a square thread, easily disconnected, to permit back-off of the coupling from the detention housing after the hold-down has been set. The other end of the detent housing is formed with a wash pipe 40a and sleeve 42 is threaded to an intermediate section of the housing. The sleeve and wash pipe provide the walls of the fluid chamber 43 and the chamber is completed in a manner to be hereinafter more fully described. The lower end of the sleeve 42 carries a tapered shoe 44 at the terminus of the outer part.

The inner part is made up of the coupling 45 for engaging the upper portion of the adjacent tubing string. The mandrel 46 extends through the locking dogs 47 and the cooperating expanding tapered shoe 44. The locking dogs have a dovetailed, tongue and groove connection with the tapered shoe. The piston-like sleeve 48 is connected to the upper end of the mandrel and its upper head provides the abutting face confronting the down turned face at the other end of chamber 43 on the detent housing. The chevron packing 58 and O-rings 59 and 59a complete the seal for the chamber. This head 48 is adapted to move between the wash pipe 40a and sleeve 42 to vary the volume of the chamber 43.

It will be noted that upon relative telescoping movement of the inner and outer parts from the position shown, in a direction to reduce the volume of chamber 43, the dogs 47 will be expanded by the tapered shoe 44 to engage the casing. This will, of course, anchor the device against upward movement due to forces generated below. Thus, if the tubing is disconnected from the device at coupling 41, the load on the lower packers will be maintained.

The chamber 43 and associated venting mechanism, provides a means for holding the device with the dogs 47 retracted, until chamber 43 has been vented. This venting mechanism is the same as that employed on the packers and includes the spring pressed valve 49 and seat 50. The pin 51 and the cam member 52 urged by leaf spring 53 into the cam notch on sleeve 54 complete the venting mechanism. The set screw 55 maintains alignment of the sleeve relative to cam member 52 by engaging the vertical slot 54b therein. The sleeve is suitably sealed above and below the opening which houses cam member 52, and a snap ring 56 holds the sleeve in one of two selected positions until forced to the other position. The 30 tapered sleeve 57 provides a stop for the upper end of the sleeve and also the interior tapers for cooperating with the dogs of the sleeve shifting tool.

It is believed that the operation of the hold-down will be apparent because it is identical to that described for the packer with the exception that the function of the hold-down is to merely hold the device against upward movement and not to provide a seal. It is set in precisely the same manner as previously described for the packer, but once set, the force from below acting upwardly maintains the dogs in engagement with the casing.

Opposite of the producing formations in the tubing string is a sleeve valve 60 for selectively establishing communication between the formation and the interior of the tubing. The sleeve valve shown is conventional equipment and is illustrated at page 1967 of the "Composite Catalog of Oil Field Equipment and Services" for 1957, 22nd edition. Only a very brief description of the sleeve valve will be given inasmuch as it is commercially available equipment.

FIG. 2 illustrates the interior of the valve on an enlarged scale. It consists of an outer housing 61 which is coupled to adjacent lengths of tubing by nipples 62 and 63. The housing has a series of perforations intermediate its ends, passage through which is controlled by the sleeve 64 interiorly of the housing. Sleeve 64 has a series of perforations adapted to register with the perforations in the housing when the sleeve is in the position shown but to be out of register when the sleeve is shifted to its lower position engaging the upper end of nipple 63. O-ring seals carried by the sleeve on each side of the perforations co-operate with the sleeve to shut off flow with the sleeve in lower position.

The size and number of openings in the sleeve may be controlled to provide in effect a choke to control the volume of flow. The snap ring 65 is adapted to engage one of the two slots formed on the inner wall of housing 61 to retain the sleeve valve member in a selected position until it is shifted by a sleeve shifting tool. The sleeve

shifting tool may be the same one that is employed for shifting the sleeves in the packers and hold-down.

With the arrangement shown in the drawings, one of the sleeve valves 60 may be opened while the others are closed so as to produce only from one of the producing formations at one time. In turn this valve may be closed and another sleeve valve opened to permit production from a different formation. With this arrangement the allowable from each formation may be produced through a single tubing string which is maintained, during periods of production, separated from the other formations. While the invention has been described principally in connection with a producing well, it will be appreciated that the same arrangement of parts could be used as a water injection well in which water could be injected either simultaneously to all of the formations, in which case the sizing of the ports can control the quantity of injection into each formation, or into only one of the formations at a time. Likewise, the system may be employed for formation fracturing or other well operations.

It will be seen that the aims and objects of the invention have been accomplished. A packer and hold-down have been provided that may be set with a predetermined load placed thereon. The setting of a series of devices may be accomplished without manipulation of the tubing in a manner to disturb the load imposed on either the device being set or of any device therebelow. The arrangement is such that the detent for maintaining the inner and outer parts against relative movement to prevent premature setting of the packing means or the hold-down dogs, may be released by remote control, as for example through the shifting of a sleeve by a wire line mechanism. The tubing string with its component parts may be assembled and installed in the well and the lowermost packer first set and loaded with a predetermined portion of the weight of the tubing string thereabove. The second packer may then be set and loaded with a predetermined load, and this procedure followed through all the packers of the series. A hold-down may be set to maintain the load on the packers without disturbing the load previously placed on them. If desired, the tubing string above the hold-down may be parted for any desired purpose, and the packers will retain their predetermined load.

From the foregoing it will be seen that this invention is one well adapted to attain all of the ends and objects hereinabove set forth, together with other advantages which are obvious and which are inherent to the apparatus.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A well tool adapted for inclusion in a tubing string of a well comprising two coaxially aligned telescoping parts connectible to separate adjacent sections of a tubing string; radially expansible means disposed to be expanded into position engaging a well casing upon movement of one of said telescoping parts toward telescopically collapsed position relative to the other of said parts; a releasable means including a sealed chamber between opposed shoulders on said parts, a fluid in said chamber under pressure sufficient to retain said parts in telescopically expanded position, and a means for releasing the fluid from the chamber, freeing the parts to move into telescopically collapsed position expanding the expansible means.

2. The well tool of claim 1 wherein the expandible means includes dogs for engaging a well casing.

3. A well packer particularly adapted for use in sealing between two strings of well pipe in a series of such strings comprising two axially aligned telescoping parts connectible to separate vertically spaced strings of well pipe; radially expandible packing means disposed between opposing surfaces on said telescoping parts to be expanded outward upon movement of one of said telescoping parts relative to the other of said parts; a releasable means including a sealed chamber having end walls which are surfaces of opposed shoulders on said telescoping parts, a fluid in said chamber under pressure sufficient to maintain the telescoping parts in telescopically expanded position, and means controllable from the surface for venting fluid from the chamber, freeing one of said telescopic parts to move into telescopically collapsed position relative to the other.

4. The combination of claim 3 wherein the means for releasing the fluid from the chamber is controllable by a wire line operated tool.

5. A well tool adapted for inclusion in a tubing string of a well comprising two axially aligned telescoping parts connectible to separate sections in a tubing string; radially expandible means disposed to be expanded into engagement with a well casing upon movement of one of said parts into telescopically collapsed position with respect to the other; a releasable means including a sealed chamber having end walls which are surfaces of opposed shoulders upon said telescopic parts, a fluid in said chamber under pressure sufficient to maintain the telescopic parts in telescopically expanded position, a vent through a wall of said chamber, and a valve disposed to control flow of fluid from said chamber through said vent, and means for opening said valve, freeing said one telescopic part to move into telescopically collapsed position to expand the expandible means.

6. The well tool of claim 5 wherein the expandible means includes dogs for engaging a well casing.

7. A well packer particularly adapted for use between two strings of well pipe in a series of such strings comprising two coaxially aligned telescoping parts connectible to separate strings of well pipe; radially expandible packing means disposed to be expanded outward from the string upon telescopically collapsing movement of one of said parts relative to the other; a releasable means disposed to retain the parts normally in telescopically expanded position, said releasable means including a sealed chamber having end walls which are opposed shoulders on coaxially aligned telescoping parts, a fluid in said chamber under sufficient pressure to support the parts in position to maintain the packing means in contracted state, a vent from said chamber, and means controlling flow through the vent including a valve disposed in said vent for releasing fluid from the chamber, freeing the parts to move into telescopically collapsed position to expand the packing means.

8. The combination of claim 7 wherein the means controlling the vent has a part engageable by a wire line operated tool for opening said valve.

9. A well tool adapted to be connected in a tubing string of a well comprising inner and outer axially aligned telescoping parts connectible to separate sections of a tubing string and having a passageway therethrough; radially expandible means disposed to be expanded outward upon telescopically collapsing movement of one of said parts relative to the other; means providing a sealed, variable capacity chamber having end walls which are surfaces on confronting shoulders carried by said inner and outer parts, a fluid in the chamber providing a load-bearing connection between the parts to hold them normally in telescopically expanded position; a vent from said chamber; a valve disposed for releasing fluid through said vent; and means for opening said valve, releasing

fluid and freeing the parts to be moved toward telescopically collapsed position to expand the expandible means.

10. The combination of claim 9, wherein the chamber is formed by two annular concentric portions of one of the parts and an annular piston-like portion on the other of said parts.

11. A well tool adapted to be connected in a tubing string of a well comprising inner and outer axially aligned parts mounted for telescopic movement and connectible to separate sections of a tubing string to provide a passageway through the tubing string and said parts; an expandible means mounted between opposing surfaces on said parts to be expanded radially outward upon telescopically collapsing movement of the parts; means including confronting shoulders carried by the inner and outer parts in position to form a variable capacity chamber therebetween; a fluid in the chamber providing a load-bearing connection between the parts to hold them normally in telescopically expanded position; a vent communicating with said chamber; a valve disposed to control fluid flow through said vent; a member movably mounted in the passageway engageable by a tool passing therethrough and operably connected to the valve for opening the vent when engaged by said tool.

12. The combination of claim 11, wherein said member is a sleeve and a cam and follower connection is provided between the sleeve and the valve.

13. In a well tool adapted for inclusion in a tubing string of a well between adjacent upper and lower sections of the tubing string, said well tool having a passageway for fluid therethrough continuous with the bore of the tubing, means providing relative movement of the sections of tubing string toward and away from each other, expandible wall engaging means, means responsive to relative movement of the sections of tubing string toward each other for expanding the wall engaging means

30 into wall engaging position and responsive to relative movement of the sections of tubing string away from each other to retract the wall engaging means, and releasable

35 means holding sections of tubing string away from each other with the expandible wall engaging means in retracted position, that improvement which comprises a pair of concentric tubular members axially reciprocable

40 relative to each other, one of said pair of members being rigidly attached to an upper section of the tubing string and the other of said pair of members being rigidly attached to the adjacent lower section of the tubing string;

45 a sealed chamber between opposed shoulders on the pair of tubular members; a fluid in said chamber normally

50 under pressure sufficient to hold said sections of tubing string away from each other retaining the wall engaging means in retracted position, and means, operable from the

55 surface of the earth, for venting fluid from said chamber.

14. In combination, a string of well casing and a

60 string of well tubing therein; a plurality of well packers made up in the tubing string having openings therethrough

65 providing parts of the passageway through the tubing string; each of the well packers having two coaxially

aligned telescoping parts connectible to separate sections

70 of the tubing string; a radially expandible packing means

disposed to be expanded into sealing contact with the

75 casing on movement of one of said telescoping parts into

telescopically collapsed relationship with the other part;

releasable means on each of the packers including a hy-

draulic chamber and a valve for releasing fluid therefrom

disposed to hold the telescoping parts normally in tele-

scopically expanded position; a trigger mechanism with

80 a sensitive member located within the passageway opera-

75 tively connected to said releasable means to release the

85 same; and a selectively operable hold-down means con-

90 nected in the tubing string to form a part thereof and

95 located above the packers, said hold-down means being

operable to engage the casing and to hold the portion of

11

the tubing string below the hold-down means against forces tending to move said tubing string in an upward direction, means releasably connecting said hold-down means to the portion of the tubing thereabove to permit disconnection, said plurality of packers being consecutively operable from the lowermost packer to the uppermost packer, whereby a selected weight of tubing may be applied to each packer in turn to force the packing means into sealing contact with the casing wall by weight of a selected portion of the tubing string thereabove, and said hold-down means may then be set to hold the pre-selected loads on the packers.
